UNITED STATES PATENT OFFICE

KAZUO KODAMA, OF PETERSBURG, TERRITORY OF ALASKA

TELEPHONE-RECEIVER MOUNTING

Application filed August 13, 1928. Serial No. 299,306.

The present invention relates to new and useful improvements in the telephony art, and the same refers more particularly to a novel mounting for telephonic receivers.

The present invention aims to provide a receiver mounting, which will not necessitate the support of the same, in the hand of the user, but permits the user to occupy his hands with other matters after the receiver has been once set in an operative position.

An important object of the invention, resides in the means employed whereby the telephonic circuit will be closed when the novel receiver is moved outwardly to an operative position.

Still another object resides in the novel circuit actuating means employed in conjunction with the receiver.

After considering the following specification and claims, other important objects and advantages of the invention, will become apparent.

In the drawings:—

Figure 1 is a front elevation of the invention.

Fig. 2 is a side elevation of the telephone set showing the novel receiver in inoperative position.

Fig. 3 is a side elevation of the telephone set with the novel receiver in operative position.

Fig. 4 is a longitudinal sectional view thru the receiver structure disclosing the manner whereby the same is connected to the telephone set casing.

Fig. 5 is a perspective view of the shell to which the receiver is pivotally connected.

Fig. 6 is a perspective view of the housing for the magnetic vibratory unit.

Fig. 7 is a perspective view of the arm operated by the receiver for actuating the switch structure.

Fig. 8 is a fragmentary vertical sectional view through the casing of the telephone set, disclosing the switch means employed for controlling the telephonic circuit.

Fig. 9 is a fragmentary horizontal sectional view through the casing, showing the contact fingers in top plan.

Fig. 10 is a perspective view of the pivotal switch arm, and

Fig. 11 is a fragmentary interior side elevation of the casing wall showing the arm movable by the receiver in position with the pivotal switch arm.

Referring to the drawings, wherein like numerals designate like parts, a box-like casing 1 represents a structure wherein the structural details of a telephone transmitter are housed. The usual mouthpiece 2 is located at the front side of the casing, these features of originality, disclosed to illustrate the relation of the novel receiver therewith.

At preferably the right side of the casing 1 and adjacent the bottom thereof, the wall is formed with an opening 3. A shell 4 preferably of cylindrical formation is provided with a circumferentially extending flange 5 at one end thereof, this flange being disposed outwardly and formed with openings through which suitable screws may be inserted for securing the shell to the side wall, and over the opening 3.

The shell is formed with an inwardly disposed flange 6 at its opposite end, and this flange is provided with a protuberance 7 on the outer side thereof.

A cylindrical housing 7 is open at one end and is adapted to contain a magnetic vibratory unit 8 of conventional design, and preferably of the diaphragm type. A plate 9 has its periphery threaded for engagement within the end of the housing 7, and for the exertion of pressure against the diaphragm 85

of the vibratory unit.

The closed ends of the housing is provided with an extension 10, of polygonal shape, and being provided with a shoulder 11, at its inner end, for bearing relation with the edge portion of the opening 3 in the casing. The conductors 12 extending from the magnetic vibratory unit are trained through the hollow extension 10 in a manner as shown in Fig. 4.

The receiver consists of an elongated substantially U-shaped megaphonic arm 13, connected at one end to the plate 9, by a suitable means. The opposite end of the arm is provided with an enlarged head 14, whereas the venturi is flared as at 15. The end of the 100

arm 13 connected to the plate 9; is provided with a laterally disposed lug 16, adapted to abut the protuberance 7 when the arm 13 is moved outwardly of the casing 1, for example, in the position shown in Fig. 3.

5 An elongated bar 17 is provided with a circular formation 18 at one end having a polygonal shaped bore 19 therethrough. An extension 10 of the housing 7 is adapted to project through the circular head 18 and a set screw may be employed as designated by 20 for securing the same in position.

15 Figs. 8 and 9 show the switch means for actuating the telephonic circuit. Suitable insulation 21 is secured to the rear wall of the casing and at the interior thereof. A pair of spring fingers 22—22, are secured at one of their ends to the insulation 21, and are separated from each other, by insulating blocks 23—23. Between the blocks 23—23 an elongated spring strip 24, has one of its ends secured, while its opposite end projects beyond the free terminals of the spring fingers 22—22.

25 An L-shaped lever 25 is flattened for a major portion of its length, and clearly disclosed in Fig. 10. A suitable bracket 26 is mounted on the floor of the casing 1 for pivotally supporting the L-shaped lever 5. A portion of the lever 25 is knurled at 27, and adapted to project through a slot 20 in the side of the casing.

30 When the arm 13 is in the position shown in Fig. 2, the bar 17 is bearing downwardly on the L-shaped lever 25, resulting in the engagement of the upstanding leg portion thereof, against the spring strip 24, for maintaining the telephonic circuit.

35 When the arm 13 is in the position shown in Fig. 3, the bar 17 is lifted from engagement upon the lever 25, which results in the movement of the spring strip 24, to a position bearing against the opposite contact 22, which results in the telephonic circuit.

40 The present invention will obviously be appreciated to a high degree in railroad stations, and similar places, where the patrons are in a rush and prefer to retain parcels and baggage in their hands, rather than to place the same upon the floor, the present device serving this need completely in that all that is necessary, is to move the megaphonic arm 13 outwardly of the casing 1, which results in the closing of the telephonic circuit and the proper disposing of the arm in respect to the transmitter mouthpiece 2.

45 It is also to be understood that certain changes in the specific shape, size, and materials, consistent with the present invention, 50 may be resorted to in the manufacture thereof, without departing from the spirit of the invention or the scope of the appended claims.

Having thus described my invention, what I claim as new is:—

55 1. In a receiver for wall type telephones

wherein the same includes a casing, an elongated megaphonic arm, a shell secured to one side of the casing, a magnetic vibratory unit attached to the reduced end of said arm and being swivelly disposed within the said shell, and complementary stop means between the arm and the shell, whereby the arm may be supported in a definite position outwardly of the casing, a switch structure for opening and closing the telephonic circuit, and means between the arm and the switch whereby the latter is operated by the movement of the arm.

2. In a telephone set comprising a casing, an ear piece movably secured to said casing, a switch for closing the usual telephonic circuit, and means operable by said ear piece for actuating said switch when the ear piece is moved to a predetermined position, said switch structure consisting of a base plate of dielectric material, a pair of stationary arms projecting from said base plate, and a spring arm projecting from the plate and beyond the free ends thereof.

3. In a telephone set comprising a casing, an ear piece movably secured to said casing, a switch for closing the usual telephonic circuit, and means operable by said ear piece for actuating said switch when the ear piece is moved to a predetermined position, said switch structure consisting of a base plate of dielectric material, a pair of stationary arms projecting from said base plate, and a spring arm projecting from the plate and beyond the free ends thereof, a rocker arm engageable at one end by the ear piece and being adapted at its opposite end to transmit motion to the spring arm for actuating the said switch.

4. In a telephone set comprising a casing, an ear piece movably secured to said casing, a switch for closing the usual telephonic circuit, and means operable by said ear piece for actuating said switch when the ear piece is moved to a predetermined position, said switch structure consisting of a base plate of dielectric material, a pair of stationary arms projecting from said base plate, and a spring arm projecting from the plate and beyond the free ends thereof, said means consisting of a rocker arm and a lever projecting laterally from the inner end of the ear piece, said lever being adapted to engage one end of the rocker arm, while the opposite end thereof is adapted to engage the spring arm to actuate the said switch when the ear piece is moved to a predetermined position.

5. In a telephone set comprising a casing, an ear piece movably secured to said casing, said casing being provided with an opening, a rocker arm mounted within the opening, one end of the arm being adapted for hand engagement, a switch for interposition in the usual telephonic circuit, and means operable by said ear piece for engaging said arm so

as to cause the same to move against and actuate the said switch.

6. In a telephone set comprising a casing, an ear piece movably secured to said casing, said casing being provided with an opening, an L-shaped rocker arm mounted within the opening, a switch for making or breaking the usual telephonic circuit, a lever on the ear piece for engaging said rocker arm, and 10 moving the same against the switch for actuating the same.

In testimony whereof I affix my signature.
KAZUO KODAMA.
